UNITED STATES PATENT OFFICE.

AMOS J. BIRTCHE, OF CERYL, NEBRASKA.

GAS-PIPE AND ROD TONGS.

SPECIFICATION forming part of Letters Patent No. 593,042, dated November 2, 1897.

Application filed August 27, 1895. Serial No. 560,718. (No model.)

To all whom it may concern:

Be it known that I, AMOS J. BIRTCHE, of Ceryl, in the county of Gosper, State of Nebraska, have invented a new and useful 5 Wrench or Pipe-Tongs, of which the following is a specification.

My invention relates to improvements in pipe and rod wrenches or tongs; and the objects are to provide an adjustable pivoted jaw 10 and govern the operation of the same in its several adjustments by a cam-faced lever. I attain these objects by the mechanism illustrated in the accompanying drawings, in which—

15 Figure 1 is a perspective view of the wrench or tongs, showing the pivoted jaw and cam-lever in full; and Fig. 2, a plan view showing the reverse side of the tool.

Similar letters refer to similar parts throughout both views.

20 *a* is the rigid jaw, having a slot *a'* extending from the rear of the jaw toward its forward end. The forward portion of the jaw is thickened, forming a curved abutment. 25 Adjacent to this, but adjustable to and from it, are the curved jaw *c* and the governor *b*. These have, respectively, concave and convex faces and are connected on both sides of the fixed jaw by links *d* by means of pins *e*, 30 which pass through the slot *a'*. The rear end of the jaw has a screw-threaded aperture in which is mounted an adjusting-screw *f*, which bears against the rear pin *e*. Operating-han-

dles *G G* are provided for the rigid jaw and the governor. The grasping-faces of the jaws 35 are preferably toothed or ratchet-faced.

The operation of my wrench is as follows: The distance between the jaws is regulated by turning the adjusting-screw in or out, thus moving the pivot-pin of the jaw *c* toward the 40 extremity of the rigid jaw or permitting the reverse adjustment. The jaws having been placed in position on the article to be operated on and the handles forced toward each other, the forward end of the governor slides 45 along the concaved rear face of the pivoted jaw, thus acting as a cam to force its grasping-face toward the corresponding face of the rigid jaw.

Having thus described my invention, what 50 I claim, and desire to protect by Letters Patent, is—

In a pipe wrench or tongs, a rigid jaw having a longitudinal slot, a second jaw having a governor bearing against its rear face, the 55 said jaw and governor connected by a link or links, and having pivot-pins extending into the slot, an adjusting-screw bearing against the pivot-pin of the governor in the slot, and handles for actuating the rigid jaw and governor as set forth. 60

AMOS J. BIRTCHE.
